UNITED STATES PATENT OFFICE.

WILLIAM L. BLISS, OF NIAGARA FALLS, NEW YORK, ASSIGNOR, BY MESNE ASSIGNMENTS, TO U. S. LIGHT & HEAT CORPORATION, OF NIAGARA FALLS, NEW YORK, A CORPORATION OF NEW YORK

LUBRICATING DEVICE.

1,221,018.

Specification of Letters Patent.

Patented Apr. 3, 1917.

Application filed May 3, 1911. Serial No. 624,87

To all whom it may concern:

Be it known that I, WILLIAM L. BLISS, a citizen of the United States, residing at Niagara Falls, in the county of Niagara and State of New York, have invented new and useful Improvements in Lubricating Devices, of which the following is a full, clear, concise, and exact description, reference being had to the accompanying drawing, forming a part of this specification.

My invention relates to lubricating devices.

It more particularly relates to lubricating devices of the type described in my prior application, Serial No. 572,489, filed July 18th, 1910, in which a lubricating chain and ring are employed to convey the oil from an oil well to a rotating shaft.

The object of my invention is to provide an improved lubricating device. A further object of my invention is to provide an improved lubricating device in which the oil is fed to the part to be lubricated regardless of the speed at which this part moves. Other objects and advantages will herein-after appear.

In the accompanying drawings I have, in order to illustrate the principle of my invention, shown one form which it may assume in practice. My invention is not, however, in any way limited to this specific form but may be used in various other forms and various other relations.

In the drawings:

Figure 1 shows a sectional view of this device in position in a suitable casing.

Fig. 2 shows a longitudinal sectional view on the line 2—2 of Fig. 1.

Fig. 3 shows a detail view of the oil ring.

In these views I have shown my improved lubricating device mounted upon a rotatable shaft 1 and inclosed in a suitable casing 2 having an oil well 3 at the bottom, and a suitable oil inlet 4 at one side of the same. The shaft 1 extends transversely through openings 5 in the opposite ends of the casing 2 as shown in Fig. 2, and is provided with a suitable sleeve-like bearing 6. This bearing has an upper cutaway portion

7 of approximately the same width as a vertically extending chamber 8 in the casing. However, the cutaway portion 7 does not extend around the entire bearing 6, but is only semi-cylindrical in cross section as

shown in Fig. 1, and is so arranged that the lower half of the bearing 6 passes through the chamber 8 and houses the lower half of the shaft 1.

Loosely mounted upon the periphery of the shaft 1 within the chamber 8 is an oil ring 9. This oil ring 9 is of a larger diameter than the diameter of the shaft and is adapted to be suspended loosely from the top surface of the shaft as shown in Fig. 1. As shown in Fig. 3 this ring 9 has a cylindrical slotted tread 10. The slots 11 in this tread are preferably arranged end to end and extend at intervals around the periphery of the tread 10. They may however, assume different forms. At the sides of the tread 10, the width of which is a trifle less than the width of the chamber 8, this tread is provided with annular flanges 12. These flanges are preferably slightly outwardly inclined or flared from the tread as shown in Fig. 3. When placed in position on the shaft, I preferably so arrange the oil ring 9 that the lower edges of the flanges 12 dip within the oil in the oil well 3 so that when the oil ring 9 is rotated by the action of the shaft, a certain amount of oil will be picked up by these flanges.

Upon the tread 10, between the flanges 12 and over the slots 11, I preferably hang a chain 13. This chain 13 has its ends connected to each other and is adapted to act as an endless conveyer for the oil. It is of such a length that it extends down into the oil well 3 as illustrated in Fig. 1, when hung loosely over the tread 10 of the oil ring 9. This chain 13 is preferably of the construction illustrated in Fig. 2, and consists of a chain of what is known as the ladder type, in which the links 14 are of substantially U-shape as shown in Fig. 2 and are provided with the hooked ends 15 which engage the U-shaped portion of the next link.

When the parts are in the position shown in Fig. 2, the flanges 12 of the oil ring 9 extend over quite close to the walls of the chamber 8 and the chain 13 lies flat upon the tread 10 of the oil ring over the slots 11, while the lower end of this chain 13 extends vertically downward into the oil well 3. Thus it is seen that when the shaft 1 is rotated, the oil in the well 3 will be picked up, partly by the chain 13 and partly by the ring 9. The oil which is picked up by the

ring will be carried to the outer edges of the flanges 12 and thrown off of the same by centrifugal action, so that it will strike the upper side walls of the chamber 8, and then flow down these walls along the outside of the flanges 12 to the shaft 1. The oil picked up by the chain 13 will, however, remain upon the chain as the chain travels with the ring 9, and will pass down through the 10 chain to the slots 11 in the tread of the ring and through these slots 11 will pass to the surface of the shaft 1. The lubricant which is supplied to the shaft 1 will tend to creep along the shaft. In order to prevent it 15 from passing off of the end of the same, I preferably provide the shaft 1 with one or more slings 16 at one or both of its ends, abutting against the ends of the bearings 6. These slings are preferably provided with 20 beveled edges 17 and are arranged adjacent a collar 18 on the shaft. Both the slings 16 and the collar 18 are preferably located in a suitable chamber 19 in the casing 2, communicating with the oil well 3 through a 25 channel 20. When the oil seeps out along the shaft to the flange 17, it is thrown off of these flanges by centrifugal action against the walls of the chamber 19, and is returned to the oil well 3 through the channel 20.

30 By my improved construction I have provided a lubricating device which is adapted to lubricate shafts which rotate at high speed since, due to the provision of the slots in the oil ring, the lubricant may readily 35 find its way to these shafts and is not prevented from reaching the same by the centrifugal action due to the high speed at which the parts are rotated, which has heretofore tended to throw it off of the oil ring 40 before it could pass through the same to the shaft. Further, my improved construction may be very compactly assembled upon a shaft and is of such rugged construction that it is capable of long use in service with 45 out any particular attention other than to occasionally supply more oil to the oil well.

While I have in this application described

one form which my invention may assume in practice, my invention itself, however, is in nowise limited to this specific form and 50 may assume various other forms and be used in various other relations, all of which fall within the scope and forethought of my present invention.

What I claim as new and desire to secure 55 by Letters Patent of the United States is:—

1. In combination, a rotatable shaft, a separable externally flanged oil ring loosely mounted on said shaft, the periphery of said ring between the flanges being provided 60 with slots which extend over a considerable arc of the circumference, an oil well in which said flanges are arranged to rotate, a chain loosely hung upon said slotted tread, and means for directing to the shaft the oil 65 picked up by the flanges in passing through said oil well and thrown off of the same by centrifugal action and said elongated slots serving to convey the oil picked up by said chain to the shaft at all speeds of rotation 70 of the shaft.

2. In combination, an oil ring having flaring flanges the periphery of said ring between the flanges being slotted, the slots extending substantially around the entire circumference, a shaft extending through said ring, said ring bearing directly on said shaft and adapted to be driven frictionally thereby, an oil receptacle into which said ring is arranged to dip, a chain loosely hung 80 upon the tread of said ring and extending downward into the oil well, and means for directing to the shaft the oil picked up by said ring, said elongated slots serving to direct the oil picked up by said chain to said 85 shaft at all speeds of rotation of the shaft.

In witness whereof, I have hereunto subscribed my name in the presence of two witnesses.

WILLIAM L. BLISS.
